UNITED STATES PATENT OFFICE.

EMMA E. CRAVEN, OF PORTLAND, OREGON.

DOG-FOOT BRACE AND SUPPORT.

1,263,744.

Specification of Letters Patent. Patented Apr. 23, 1918.

Application filed March 13, 1917. Serial No. 154,463.

To all whom it may concern:

Be it known that I, EMMA E. CRAVEN, a citizen of the United States, residing at Portland, in the county of Multnomah, State 5 of Oregon, have invented a new and useful Improvement in Dog-Foot Braces and Supports, of which the following is a specification, reference being had to the accompanying drawings.

10 My invention relates to a class of devices more particularly applicable to the feet of dogs.

The object of my invention is to provide a device in the nature of a dog-foot brace or support which supplies the means to support or brace the foot when the latter is adjusted to or nearly to its normal form. I attain this object, as well as others, by the construction, combination and arrangement 20 of parts, illustrated in the accompanying drawings which form a part hereof.

Figure 1 is a front view of the device in perspective.

Fig. 2 is a side view of the device in perspective.

Fig. 3 is a perspective view of the device from the lower end thereof.

Fig. 4 is a developed pattern view of the left one-half of the device when the straps 30 are disengaged.

Fig. 5 is a similar view of the right one-half and buckles thereon.

Fig. 6 is a developed pattern view of the outside upright reinforcing strip.

Fig. 7 is a developed pattern view of the lower lateral inside reinforcing strip.

Fig. 8 is a perspective view of normal dog feet.

Like numerals refer to like parts throughout the views.

The device is composed of a body 9, which is a two-part piece of soft leather cut to a form which will fit snugly around the lower part of a dog's foot. The two parts of the 45 body 9 are sewed together at their joining edges. The body is reinforced in front by a lateral leather yoke 10 and a longitudinal strip 11 each sewed to the body. From the upper part of one end of the body 9 a short 50 integral strap 12 extends, and from the lower part of the same end of the body a longer integral strap 13 extends, both being perforated with buckle holes 14. From the upper part of the opposite end of the body 55 9 a strap 15 extends a suitable distance and has a buckle 16 secured at its end. From

the lower part of the same end of the body another strap 18 extends a suitable distance and has a buckle 19 secured at its end. In one side of the body 9 is an opening 20. 60 Vertically below the opening 20 on the exterior of the body 9 is a loop 21 through which the strap 18 passes. At a suitable distance from the inner end of the strap 15 is a slit 22 in the body 9 and through this 65 the strap 12 passes. At a suitable distance from the inner end of the strap 18 is a slit 23 in the body 9, through which the strap 13 passes. From thence the strap 13 passes around the front of the body 9 and through a loop 24 on the exterior of the body, and thence the strap 13 passes underneath the body and through a second loop 25 on the opposite side of the former near its lower end. All of the said slits and loops are located and arranged in and upon the body 9 in a manner to allow the straps to pass 70 through them as described, and be buckled together; with the object in view of retaining the device about the foot in an operative 75 position to brace or support parts of the foot as desired without displacement of any part of the straps or the binding thereof in a manner not contemplated, which might interfere with such object. It is essential that 80 the loop 21 shall be vertically below the opening 20. For facility in description, dog-feet are illustrated in Fig. 8. There are shown the forefeet 26, the angles or pasterns 27 and the dewclaws 28. 85

It will be now observed that when my device is placed about a dog's foot the dewclaws 28 extend through the opening 20 of the body 9 and engage the edge of the body below it in the opening. The body then encircles the foot and the upper straps 12 and 13 are buckled together. The strap 13 is adjusted between the ball and toes of the foot and buckled to the strap 18. The straps are buckled sufficiently together to retain the 90 device upon the foot in snug fitting position, after the foot is adjusted to or nearly to normal form. The device may be made of leather or suitable soft material. The yoke and reinforcing strip are of advantage 95 in retaining the device in place and strengthening it. The yoke may be of soft felt or suitable material to act upon the toes with much benefit. 100

It is well known that dogs, and particularly dogs with heavy bodies and small feet, as in the case of bull dogs, are often trouble² 110

with dislocated ankles, broken arches, splayed feet, sprained or weak ankles or they may be down on their pasterns. These troubles seriously interfere with or prevent the animals' movements in walking or running, and affect their health. I contend that I have provided a brace and support which can be fitted to the foot in a manner to restore or retain the normal foot-form, and at the same time to fit like a glove and be comfortable and convenient to the animal. It is so arranged that it does not bind or become displaced and will adjust itself automatically to the foot, notwithstanding the movements thereof. By means of the device, dislocated bones may be held in position to recover normal condition, and weak ankles or arches are braced and supported until strengthened, and splayed feet greatly benefited or cured. When the device is in use upon an animal it can take its natural exercise comfortably and easily, because of the excellent fit and adaptability of the brace, which in no way causes the animal any annoyance. It may be removed at night or when the dog is not exercising.

I claim:

1. A brace and support for a dog foot comprising in combination, first, a body of soft material tapering from its lower to upper end and formed to be conveniently adjustable to a dog foot shape, said body being provided with an opening in one side thereof in a position to allow a dew-claw to extend through same and engage the edge of the body in the opening, a strap loop 21 on the body below the opening, a strap loop 24 on the body in front of the loop 21, a slit 23 in and near the opposite end of the body, a strap loop 25 on the same part of the body in front of the slit 23 and oppositely disposed to the loop 24, said slit and loops being arranged at desired angles to the vertical direction of the body, second, strap means upon the ends of the upper part of the body, adaptable to secure the body around a dog foot, third, a strap extending from the lower part of one end of the body, adjustable through the loop 21 and over the lower, forward part of the body, with securing means on the strap, fourth, a strap of desired length extending from the lower part and opposite end of the body, adjustable through

the slit 23, thence around the front of the body through the loop 24, thence below the body between the ball and toes of a dog foot, thence through the loop 25 to a position securable to the opposing lower body strap, all in a manner to retain the body and straps snugly to and upon a dog foot when the same has been adjusted to or nearly to a normal form, substantially as stated.

2. A brace and support for a dog foot comprising in combination, first, a body of soft material tapering from its lower to upper end and formed to be conveniently adjustable to a dog foot shape, said body being provided with an opening in one side thereof in a position to allow a dew-claw to extend through same and engage the edge of the body in the opening, a strap loop 21 on the body below the opening, a strap loop 24 on the body in front of the loop 21, a slit 23 in and near the opposite end of the body, a strap loop 25 on the same part of the body in front of the slit 23 and oppositely disposed to the loop 24, said slit and loops being arranged at desired angles to the vertical direction of the body, second, strap means upon the ends of the upper part of the body, adaptable to secure the body around a dog foot, third, a strap extending from the lower part of one end of the body, adjustable through the loop 21 and over the lower, forward part of the body, with securing means on the strap, fourth, a strap of desired length extending from the lower part and opposite end of the body, adjustable through the slit 23, thence around the front of the body through the loop 24, thence below the body between the ball and toes of a dog foot, thence through the loop 25 to a position securable to the opposing lower body strap, all in a manner to retain the body and straps snugly to and upon a dog foot when the same has been adjusted to or nearly to a normal form, fifth, a lateral yoke of suitable soft material secured to the inner surface of the lower forward part of the body in a position to engage a dog foot across the front of the pastern, substantially as described.

EMMA E. CRAVEN.
